UNITED STATES PATENT OFFICE.

GOLDWIN SMITH, OF TAMPA, FLORIDA.

BASEBALL GAME.

Application filed May 9, 1927. Serial No. 189,948.

The invention relates to mechanical base ball games particularly adapted to be played indoors.

The objects of the invention are to provide simple efficient and practical means whereby the game of baseball may be simulated; to provide means whereby the skill of the players of said game is adapted to effect the final score and by which the most skillful 10 player acquires the highest score and therefore is the successful participant of the several players.

The invention consists in the combination, arrangement of the parts and in the details 15 of the construction, as herein set forth and claimed.

In the drawings:

Fig. 1 is a plan elevation of the invention;

Fig. 2 is a section taken on a line corresponding to 2—2 in Fig. 1;

Fig. 3 is an enlarged detailed side elevation of a fence picket;

Fig. 4 is a section, with parts removed, taken on a line corresponding to 4—4 in Fig. 25 1; and

Fig. 5 is a section, with parts removed, taken on a line corresponding to 5—5 in Fig. 1.

In the preferred construction of the invention I provide cylindrical drum 1 comprising sides 2, bottom 3, and top 4. The top has a centrally disposed perforation or hole 5 therein. From the hole 5 the top 4 slopes upwardly and outwardly, whereby a sphere or ball is adapted, by the force of the gravitation, to be carried from any point on the top toward and into the hole 5.

Fixed to the center of the bottom 3 is the rotatable spindle 6 having operative connection, through shaft 7, with manually rotatable crank 8 which is positioned for convenient operation of the players. Any suitable mechanism 9 may be utilized to impart rotation to the spindle 6 through manual rotation of the crank 8. In Fig. 2 is shown, integral with the inner end of the shaft 7, the worm 10 which meshes with the usual worm gear 11 suitably fixed to the spindle 6. For safety purposes the worm 10 and the gear 11 are enclosed within the casing 12 having its upper edge suitably secured to the trough 12', hereinafter fully described. The speed and direction of rotation of the drum 1 may be controlled by manual operation of the 55 crank 8 or if desirable, suitable braking

mechanism may be incorporated in the casing 12 for the purpose of enabling the players of the game to more effectually reduce the velocity at which the drum 1 rotates, by means of manual operation of the crank 8, whereby the movement of the ball may be controlled. If braking mechanism is utilized it may be desirable to permit the crank 8 to be revolved only in one direction for rotating the drum and to incorporate other mechanism by which when the direction of rotation of the crank is reversed the rotatable speed of the drum is retarded. The crank shaft 7 is retained in operative position, with respect to the worm gear, as by strap bearing 13 suitably secured to the bottom of trough 12'. The bearing 6', around spindle 6, is to prevent lateral movement of the drum.

Surrounding the drum 1 and adjacent thereto is stationary circlet or inner field 14 having holes 15, 16, 17 and 18 positioned therein at points separated by 90° to represent home plate, first base, second base, and third base, respectively, of the invention. Intermediate holes 15 and 16, 16 and 17, 17 and 18, and 18 and 15, are ridges 19, 20, 21 and 22 elevated from the position of the holes 15, 16, 17 and 18. Also, the inner and outer surfaces 23 and 24 of the circlet 14 slope inwardly and downwardly toward and adjacent holes 15, 16, 17 and 18, whereby a sphere or ball positioned at any point between the ridges 19 and 20, 20 and 21, 21 and 22, and 22 and 19, is adapted to be carried, by gravitation, into one of the holes 15, 16, 17 and 18, respectively.

The inner edge 25 of the circlet is slightly overlapped by the outer edge 26 of the drum 1 and actual contact of the revolving drum with the circlet is avoided.

Surrounding the outer edge 27 of the circlet 14, except at opening 28 between points 29 and 30, is fence 31 comprising pickets 32, connected to resilient members, or coiled springs 33, suitably secured to the outer edge of the circlet.

Integral with the outer edge 27 of the circlet 14 is edge 34 of circular band or outer field 35 which surrounds the circlet. The band 35 has a plurality of spaced apart orifices 36 therein and intermediate the respective ridges 37. The inner edge 34, outer edges 38 and the surface of the band 35 slopes downwardly toward the holes 36, whereby a sphere or ball positioned at any point upon

the surface of the band is adapted to be carried, by gravitation, to the hole 36 which is located between the adjacent ridges 37, between which the ball or sphere is placed. In 5 other words, the ridges 37 of the band 35 sub-divide the surface thereof in such a manner that the surface adjacent the respective holes 36 slope downwardly thereto.

Surrounding the band 35 is guard 39 10 comprising spaced apart strands 40 secured to standards 41 fixed in the outer edge 38 of the band. Secured to the top 42 of the guard 39 is railing 43 curved downwardly.

In practice the casing 44 may support 15 the outer edges of the band 35. The casing 44 is supported by counter or table 45 comprising top 46 and legs 47. At the front 45' of the counter is bin 48 having connection with trough 12' inclined downwardly 20 toward bin. The trough is connected with the sides of the casing and is positioned below the perforation 5, the holes 15, 16, 17 and 18, and the orifices 36, whereby when a ball is received by either of the holes, 25 orifices or the perforation it is automatically conveyed by the trough into the bin 48 for convenient access of the players of the game. When the ball is received by perforation 5 it falls upon bottom 3 drum 1, from where 30 the ball passes through hole 49, in bottom 3 of the drum, into the trough.

Suitably secured to the drum 1, near its outer edge, is basket 50, tapered downwardly for containing the ball for use in 35 playing the game.

In playing the game, a ball is placed into the basket 50 from which position it is removed by gravitation from the hole 51 in the bottom of the basket. After the ball is 40 removed from the basket and is positioned upon the upper surface of the top 4 of the drum, the skill of the player, in operating the crank 8 to rotate the drum 1 at the proper speed, determines whether the ball 45 will roll down the slope of the top 4 into hole 5, or whether it will be forced upon the circlet 14 and into one of the holes 15, 16, 17 or 18, or whether it will be forced over the fence 31, or through the opening 28, 50 upon the band or outer field 35 and into one of the orifices 36. The upwardly extending projection 30' in the circlet, adjacent point 30 tends to control the movement of the ball.

55 The characters 52 may be positioned upon the tops of pickets 32, so that if the ball contacts one of the characters and dislodges it from the picket this result may count a predetermined number of points, or portion 60 of a point, in favor of the player who operates the invention.

It may be desirable to secure to the top 46 of the counter 45 an automatic score board 53, of usual design, which may be arranged to automatically register upon its 65

face the scores effected by the players and depending upon the hole, orifice or perforation which receives the ball.

The game may be played by any suitable rules. However, I have found the following 70 method of counting points to be interesting: Where a ball enters hole 16 the player gains five points, hole 17, ten points, hole 18, fifteen points, hole 19, twenty points. Where the ball enters hole 36 or perforation 5, or 75 dislodges a character 52 from a picket, the points in favor of the player may be arranged according to the difficulty in preventing or accomplishing the feat.

At the completion of a game the points 80 acquired by a player are added and his winning, or being the successful participant in the game, depends upon whether he has earned a greater number of points than other players.

85 If desirable, a coin operated apparatus may be positioned at the point 54. This apparatus may have suitable connection with the mechanism of the invention whereby it is necessary for a player to deposit a coin in 90 the apparatus to play the game. Moreover, a suitable lighting system, may be incorporated in the structure of the invention.

95 It is apparent that I have invented a highly desirable device for the purposes intended and which may be the means of providing enjoyable recreation of simulating playing the national game of baseball.

100 The rules for playing the game may be varied in accordance with the different circumstances and dependent upon the desires of the manufacturers, operators, and players of the game.

105 While I have chosen to illustrate the form and construction of the invention by the herein drawings and explanations of the same, it is understood that the invention resides in the combination, arrangement of the parts and in the details of the construction, as hereinafter claimed. It is further understood that changes in the precise embodiment of the invention, as disclosed herein, can be made within the scope of what is claimed without departing from the spirit of the invention, as other expedients may 110 readily suggest themselves to the art.

115 What I claim as new and desire to secure by Letters Patent is:

1. In a device of the class described a ball, a rotatable drum having a perforation 120 in its center and having its top sloping upwardly from the center to its outer edge, a stationary circlet surrounding said drum and said circlet having a plurality of holes therein to receive said ball and manually operative means to rotate said drum, substantially as and for the purposes specified.

125 2. In a device of the class described, a rotatable drum, a stationary circlet surrounding said drum having its top sloping 130

upwardly from its center to its outer edge and having a perforation at its center and said circlet having a plurality of holes therein, a band surrounding said circlet and 5 having a plurality of orifices therein, and manually operative means to rotate said drum.

3. In a device of the class described, a rotatable drum, a stationary circlet surrounding said drum and said circlet having a plurality of holes therein representing home plate, first base, second base and third base, the surface of said circlet sloping toward said holes, and the surface of said 15 drum sloping upwardly from its center toward its outer edge and said drum having a hole at its center, and manually operative means to rotate said drum, substantially as and for the purposes specified.

20 4. In a device of the class described a rotatable drum, having a top having a centrally disposed hole therein, the top sloping toward said hole, a stationary circlet surrounding said drum and said circlet having a plurality of holes therein, the surface of 25 said circlet sloping downwardly toward said holes, a band surrounding said circlet and having a plurality of orifices therein, the surface of said band sloping toward said orifices, manually operative means to rotate said drum, and a ball placed on said drum and adapted to be received by one of said 30 orifices, or holes substantially as and for the purposes specified.

35 5. In a base ball game, the combination with a ball, of a rotatable drum having a perforation in its top to receive said ball, the surface of said top sloping toward said perforation, an inner field comprising a circlet having four holes therein to receive said ball, said holes representing home plate, first base, 40 second base, and third base, the surface of said circlet sloping toward said holes, an outer field comprising a circular band having a plurality of orifices therein to receive said ball, the surface of said band sloping toward said 45 orifices, a return bin for said ball, means to convey the ball from said perforation, holes and orifices to said bin, manually operative means to rotate said drum whereby said ball is caused to be received by one of said holes, orifices or perforations, substantially as and for the purposes specified.

50 6. In a base ball game, the combination with a ball, of a rotatable drum having a perforation in its center to receive the ball, the surface of said top sloping toward said perforation, an inner field comprising a circlet having four holes therein to receive said ball, said holes representing home plate, first base, second base, and third base, the surface of said circlet sloping toward said holes, an outer field comprising a circular band having a plurality of orifices therein to receive said ball, the surface of said field sloping toward said orifices, and manually operative 55 means to rotate said drum whereby said ball 60 is caused to be received by one of said holes, orifices or perforations, substantially as and for the purposes specified.

is caused to be received by one of said holes, orifices or perforation, substantially as described.

7. In a base ball game, the combination with a plurality of balls, of a rotatable drum having a perforation in its top to receive said balls, the surface of said top sloping toward said perforation, an inner field comprising a circlet having four holes therein to receive said balls, said holes representing home plate, first base, second base, and third base, the surface of said circlet sloping toward said holes, an outer field comprising a circular band having a plurality of orifices therein to receive said balls, the surface of 75 said band sloping toward said orifices, a fence intermediate said inner field and said outer field, a return bin for said balls, a trough to receive said balls from said perforation, holes and orifices and to convey 80 the same to said bin, a basket to retain said balls before each play, and manually operative means to rotate said drum whereby one of said balls is caused to be received by one of said holes, orifices or perforation, substantially as and for the purposes described.

8. In a base ball game, the combination with a counter and a ball, of a rotatable drum having a perforation in its top to receive said ball, the surface of said top sloping toward said perforation, an inner field comprising a circlet having four holes therein to receive said ball, said holes representing home plate, first base, second base, and third base, the surface of said circlet sloping toward said holes, an outer field comprising a circular band having a plurality of orifices therein to receive said ball, the surface of said band sloping toward said orifices, a return bin for said ball, means to 100 convey the ball from said perforation, holes and orifices to said bin, manually operative means to rotate said drum whereby said ball is caused to be received by one of said holes, orifices or perforations, substantially as 105 described.

9. In a base ball game, the combination with a counter and a plurality of balls, of a rotatable drum having a perforation in its top to receive said balls, the surface of said top sloping toward said perforation, an inner field comprising a circlet having four holes therein to receive said balls, said holes representing home plate, first base, second base, and third base, the surface of said circlet sloping toward said holes, an outer field comprising a circular band having a plurality of orifices therein to receive said balls, the surface of said band sloping toward said orifices, a return bin for said balls, an inclined trough to receive the balls from said 120 perforation, holes and orifices and conveying the same to the bin, a basket to retain said balls before each play, manually operative means to rotate said drum whereby one 125 is caused to be received by one of said holes, orifices or perforations, substantially as and for the purposes specified.

of said balls is caused to be received by one of said holes, orifices or perforations, substantially as and for the purposes described.

10. In a base ball game, a rotatable drum having a top sloping downwardly toward the center thereof, and said top having perforation therein, a circlet surrounding said drum and having a plurality of holes therein to represent home plate, first base, second base, and third base and the upper surface of said circlet adjacent said holes sloping downwardly toward said holes, an outer field surrounding said circlet and having a plurality of orifices therein, the surface of said outer field sloping downwardly toward said orifices, manually operative means to rotate the drum at a predetermined speed whereby when a ball is placed upon the top of said drum said ball is adapted by the centrifugal force of said drum to be forced upon said circlet and carried into one of said holes, and when the rotatable speed of said drum is increased said ball instead of entering one of said holes is adapted to be forced onto said outer field to be received by one of said orifices, and when the rotatable speed of said drum is sufficiently reduced said ball instead of traveling from said drum onto said circlet and outer field is adapted to be carried by gravitation into said perforation.

11. In a device of the class described, a rotatable drum having a top sloping downwardly toward the center thereof, and said top having a perforation therein, a circlet surrounding said drum and having a plurality of holes therein representing home plate, first base, second base, and third base and the upper surface of said circlet adjacent said holes sloping downwardly toward said holes, a fence surrounding said circlet, except at a point intermediate said home plate and said first base, and said fence comprising a plurality of coiled springs secured in spaced apart relation to the outer edge of said circlet, and a picket attached to each of said springs, a character releasably secured to each of said pickets, a band surrounding said circlet and having a plurality of orifices therein, the upper surface of said outer field adjacent said orifices sloping downwardly towards said orifices, a guard surrounding said band and having a railing thereon, manually operative means to rotate said drum whereby when a ball placed upon the top of said drum said ball is adapted, by the centrifugal force of said drum, to be forced upon said circlet and carried into one of said holes, and when the rotatable speed of said drum is increased said ball instead of entering one of said holes is adapted to be forced over said fence, detach one of said characters from said pickets and travel onto said band to be received by one of said orifices, and when the rotatable speed of said drum is sufficiently reduced said ball instead of traveling from said drum onto said circlet is adapted to be carried by gravitation into said perforation, a common return bin for the balls, and a trough connecting said perforations, holes and orifices with said bin.

12. In a device of the class described, a rotatable drum having a top sloping downwardly toward the center thereof, and said top having a perforation therein, a circlet surrounding said drum and having a plurality of holes therein representing home plate, first base, second base, and third base and the upper surface of said circlet adjacent said holes sloping downwardly toward said holes, an outer field and the upper surface of said circlet adjacent said holes sloping downwardly toward said holes, a fence surrounding said circlet, except at a point intermediate said home plate and said first base, and said fence comprising a plurality of coiled springs secured in spaced apart relation to the outer edge of said circlet, and a picket attached to each of said springs, a character releasably secured to each of said pickets, a band surrounding said circlet and having a plurality of orifices therein, the upper surface of said outer field adjacent said orifices sloping downwardly towards said orifices, a guard surrounding said band and having a railing thereon, manually operative means to rotate said drum whereby when a ball placed upon the top of said drum said ball is adapted, by the centrifugal force of said drum, to be forced upon said circlet and carried into one of said holes, and when the rotatable speed of said drum is increased said ball instead of entering one of said holes is adapted to be forced over said fence, detach one of said characters from said pickets and travel onto said band to be received by one of said orifices, and when the rotatable speed of said drum is sufficiently reduced said ball instead of traveling from said drum onto said circlet is adapted to be carried by gravitation into said perforation.

13. In a device of the class described, a rotatable drum having a top sloping downwardly toward the center thereof, and said top having a perforation therein, a circlet surrounding said drum and having a plurality of holes therein representing home plate, first base, second base, and third base and the upper surface of said circlet adjacent said holes sloping downwardly toward said holes, an outer field and the upper surface of said circlet adjacent said holes sloping downwardly toward said holes, a fence surrounding said circlet, except at a point intermediate said home plate and said first base, and said fence comprising a plurality of coiled springs secured in spaced apart relation to the outer edge of said circlet, and a picket attached to each of said springs, a character releasably secured to each of said pickets, a band surrounding said circlet and having a plurality of orifices therein, the upper surface of said outer field adjacent said orifices sloping downwardly towards said orifices, a guard surrounding said band and having a railing thereon, manually operative means to rotate said drum whereby when a ball placed upon the top of said drum said ball is adapted, by the centrifugal force of said drum, to be forced upon said circlet and carried into one of said holes, and when the rotatable speed of said drum is increased said ball instead of entering one of said holes is adapted to be forced over said fence, detach one of said characters from said pickets and travel onto said band to be received by one of said orifices, and when the rotatable speed of said drum is sufficiently reduced said ball instead of traveling from said drum onto said circlet is adapted to be carried by gravitation into said perforation.

14. In a device of the class described, a rotatable drum having a top sloping downwardly toward the center thereof, and said top having a perforation therein, a circlet surrounding said drum and having a plurality of holes therein representing home plate, first base, second base, and third base and the upper surface of said circlet adjacent said holes sloping downwardly toward said holes, an outer field and the upper surface of said circlet adjacent said holes sloping downwardly toward said holes, a fence surrounding said circlet, except at a point intermediate said home plate and said first base, and said fence comprising a plurality of coiled springs secured in spaced apart relation to the outer edge of said circlet, and a picket attached to each of said springs, a character releasably secured to each of said pickets, a band surrounding said circlet and having a plurality of orifices therein, the upper surface of said outer field adjacent said orifices sloping downwardly towards said orifices, a guard surrounding said band and having a railing thereon, manually operative means to rotate said drum whereby when a ball placed upon the top of said drum said ball is adapted, by the centrifugal force of said drum, to be forced upon said circlet and carried into one of said holes, and when the rotatable speed of said drum is increased said ball instead of entering one of said holes is adapted to be forced over said fence, detach one of said characters from said pickets and travel onto said band to be received by one of said orifices, and when the rotatable speed of said drum is sufficiently reduced said ball instead of traveling from said drum onto said circlet is adapted to be carried by gravitation into said perforation.

stead of entering one of said holes is adapted to be forced onto said outer field to be received by one of said orifices, and when the rotatable speed of said drum is sufficiently reduced said ball instead of traveling from said drum onto said circlet and said outer field is adapted to be carried by gravitation into said perforation, a common return bin for the balls and a trough connecting said 10 perforations, holes and orifices with said bin.

14. In a base ball game, a rotatable drum having a top sloping downwardly toward the center thereof and said top having a perforation therein, a circlet surrounding 15 said drum and having a plurality of holes therein to represent home plate, first base, second base, and third base and the upper surface of said circlet adjacent said holes sloping downwardly toward said holes, a 20 fence surrounding said circlet except at a point intermediate said home plate and said first base and said fence comprising a plurality of coiled springs secured to outer edge of said circlet, and pickets secured to the 25 said springs, characters releasably secured to each of said pickets, an outer field surrounding said circlet and having a plurality of orifices therein, the upper surface of said outer field adjacent said orifices sloping 30 downwardly and having a railing thereon,

manually operative means to rotate said drum whereby the rotatable speed of said drum is controlled, whereby a ball placed upon the top of said drum is adapted by the centrifugal force to be forced upon said circlet and carried into one of said holes, and when the rotatable speed of said drum is increased said ball is adapted to be forced over said fence, detach one of said characters from said pickets and travel onto said outer field to be received by one of said orifices and when the rotatable speed of said drum is sufficiently reduced said ball instead of traveling from said drum onto said circlet and said outer field is adapted to be carried by 45 gravitation into said perforation, and the number of balls received by said holes, orifices and perforations indicating the skill of the player in operating said game.

15. In a device of the class described, a ball, 50 a rotatable drum having a perforation in its top, said top sloping downwardly toward said perforation, a stationary circlet surrounding said drum and said circlet having a plurality of holes therein to receive said 55 ball and manually operative means to rotate said drum, substantially as and for the purposes specified.

GOLDWIN SMITH.
